CLAIM

The ornamental design for an adjustable grinder, as shown and described.

DESCRIPTION

FIG. 1 is a front, top, and right side perspective view of an adjustable grinder;

FIG. 2 is a front elevational view thereof, the rear elevational view being a mirror image of the front elevational view shown;

FIG. 3 is a right side elevational view thereof, the left side elevational view being a mirror image of the right side elevational view shown;

FIG. 4 is a top plan view thereof; and,

FIG. 5 is a bottom plan view thereof.

The broken lines in the drawings depict environmental subject matter only and form no part of the claimed design.

1 Claim, 4 Drawing Sheets
